UNITED STATES PATENT OFFICE.

ADELBERT R. GIBSON, OF LOS ANGELES, CALIFORNIA.

CONCEALED NASAL INHALER.

1,200,338.

Specification of Letters Patent. Patented Oct. 3, 1916.

Application filed February 28, 1916. Serial No. 80,976.

To all whom it may concern:

Be it known that I, ADELBERT R. GIBSON, a citizen of the United States, residing at Los Angeles, in the county of Los Angeles and State of California, have invented a new and useful Concealed Nasal Inhaler, of which the following is a specification.

The present invention relates to an improvement in that type of inhalers adapted to be fitted in the nostrils of the nose, and to be held there by engagement with the nose, the invention having among its objects to provide a simple, neat and attractive device embodying simplicity in its construction, and which when in position is practically entirely concealed, so that it cannot readily be detected; which is of peculiar form to fit in the nostrils, and to be completely inserted therein, but not sufficiently to irritate or injure the nose, and to thus obtain the highest efficiency of the device, which cannot accidentally fall or work down; and which is provided with opposed projections yieldingly binding therebetween the opposite sides of the cartilage septum of the nose to hold the inhaler in place by its own inherent resiliency, so that it does not have to be held in place by the hand, or other external means, and so that it may be used or worn continuously through a day, a night, or for any other length of time desired.

Another object of this invention is to provide a device made from a single length of wire, so peculiarly bent and rounded as to provide opposed tapering containers for fitting in the opposite nostrils of the nose; to provide a bridge piece of substantially the form of a three-quarter ring, adapted to spring over the lower edge of the cartilage septum and engage at its ends against the opposite sides thereof and hold the ring firmly and detachably in place; to provide spring connectors on the ends of the ring peculiarly joining the containers to the bridge piece to admit the automatic and independent adjustment of the containers in the nostrils, and to offset the containers downwardly and prevent irritation and injury to the nose; and to provide a retaining ledge or support at the base end of each container to hold an absorbent, such as cotton, or the like, in the containers.

Further objects of the invention are to provide an attachable concealed nasal inhaler embodying all of the above features of advantage, and which is relatively small in

construction; may be economically manufactured, and handled; may be easily packed to advantage for shipment or display; may be easily and quickly inserted in, and withdrawn from the nose; which is held in the nose by the bridge piece alone and does not depend upon the frictional engagement of the containers in the nostrils to hold the inhaler in place; and which may be worn in the nose for any desired length of time, without adjustment or attention, except to replenish the medicament used, which gradually evaporates and is drawn into the nasal passages and throat by the natural respiration through the nose.

Various other objects and advantages of this invention will be brought out in the following specific description of the present preferred embodiment of the invention, which is shown in the accompanying drawings, wherein—

Figure 1 is a perspective view of an inhaler, embodying the features of this invention, as applied to the nose, the figure showing clearly in full lines the lower portion of the bridge, which is the only part of the inhaler visible when applied. Fig. 2 is a front elevational view of the inhaler, enlarged. Fig. 3 is a longitudinal section, showing in dotted lines the outlines of the nose. Fig. 4 is a detail bottom plan view of one of the containers and the adjacent side of the bridge piece.

Referring to this drawing, wherein like parts are designated by similar numerals of reference throughout the several views, the inhaler of the present invention comprises a bridge piece 10, inturned opposed projections 11 on the bridge piece adapted to bind against the cartilage septum, indicated in Fig. 3 in dotted lines at 12, opposed spring connectors 13 and 14, and a pair of opposed upwardly tapering containers 15 and 16. The containers are each provided with a filler 17 of an absorbent material, such as cotton, held in place by an annular ledge 18, at the bottom of each container, and also having a substantially central longitudinal air passage 19 therethrough, through which air is adapted to be drawn upwardly in contact with the filler for evaporating and carrying off the medicament with which the filler is saturated.

All of these parts are peculiarly formed and assembled by bending and rolling a single length of wire in the peculiar manner

according to this invention. Referring particularly to Fig. 3, it will be observed that this single length of wire is bent into substantially U-shape, and has its intermediate portion rounded to provide the bridge piece 10 in the form of a three-quarter ring adapted to straddle or project over the lower edge of the cartilage septum 12, the free ends of the ring 10 forming the projections 11 which bind therebetween the cartilage septum, so as to yieldingly and detachably hold the length of wire in place. From the projections 11, each end or strand of the wire is bent outwardly at a slight angle to provide a pair of diverging supporting arms 20, which merge into the ends of the bridge or ring 10 and which provide therewith rounded engaging or bearing faces for the projections 11, so as not to injure or irritate the nose. The strands of wire are returned outwardly of the arms 20 and flare away therefrom to provide braces 21, and which, together with the supporting arms 20, provide substantially V-shaped spring connectors at the opposite sides of the bridge 10. From the outer or lower ends of the braces 21, the strands of the length of wire are wound spirally upward, are offset outwardly from the spring connectors 13 and 14, and provide coils consecutively decreasing in diameter from bottom to top; to thus provide a pair of opposed upwardly tapering containers which are supported upon and are integral with the spring connectors 13 and 14. The braces 21, or outer sides of the spring connectors 13 and 14, lie close against the convolutions or coils of the wire at the enlarged or base portions of the containers 15 and 16, and extend longitudinally thereof to brace and support the containers. As the connectors 13 and 14 are of substantially V-shape, the angle thereof admits of a substantial flexing of the connectors with relatively light pressure, so that the containers 15 and 16 are free, to a large extent, to adapt themselves automatically to conditions of the nostrils and to the thickness of the cartilage septum. The lower enlarged ends of the containers 15 and 16, comprising the base ends of the containers, are provided with the annular ledges 18, which are formed by reducing the lowermost coil or helix of each container in diameter, so that the coil or helix lies within the conical planes of the containers, and thus provides an inwardly extending ledge 18 in the bottoms of the containers to support the filler 17.

In following the single length of wire, one end 22 thereof lies at the top of the container 15, and is wound spirally downward, the coils being consecutively enlarged in diameter until the container 15 is reached, when the last helix or coil is curved on a reduced diameter to provide

the ledge 18. The length of wire is carried from the inner side of the ledge 18 upwardly at an abrupt angle, and bears against the outer faces of the lowermost helices at the inner side of the container 15, to provide the brace arm 21. The upper end of the brace arm is then returned downwardly and inwardly, to form the supporting arm 20. The length of wire is continued from the lower end of the supporting arm 20 downwardly and rounded to provide the bridge piece or ring 10. In further following the single length of wire, the opposite side of the bridge piece 10 merges into the opposite supporting arm 20, the adjacent downwardly extending brace arm 21, the reduced helix or ledge 18 of the opposite container 18, and is then wound upwardly, the coils of which consecutively decrease in diameter to form the opposite container 16. The length of wire terminates at its opposite end at 23, at the top of the container 16.

By the provision of the V-shaped connectors 13 and 14, the containers 15 and 16 are offset downwardly upon the bridge 10, so that the upper reduced ends of the containers do not come in contact with the walls of the nostrils, and thus are held downwardly at a distance sufficient to prevent injury or irritation of the nose, and at the same time the containers are held so that they are not visible when applied. The bridge 10, which engages upwardly about the lower edge of the cartilage septum, is the only portion of the inhaler which may possibly be observed. When the device is worn during the day, the nose, projecting outwardly and over the bridge 10, hides the latter substantially entirely from view, so that it may only be detected upon close inspection. The device is small and light in weight, and thus requires but a relatively slight pressure of the projections 11 in the nose, and consequently the presence or application of the device is scarcely felt.

In the use of this improved inhaler, the filler or absorbent material 17 is saturated with the desired medicament. The device is then pressed into the nose with the reduced ends of the containers 15 and 16 in registry with the nostrils. As the bridge piece 10 is forced upwardly, the outwardly flaring or inclined supporting arms 20 act as cam faces to spread the bridge piece 10, and guide the same into position over the lower edge of the cartilage septum. The provision of these V-shaped connectors offsets the containers 15 and 16 outwardly from the bridge piece 10, and thus centers the containers in the nostrils. It is thus seen that the containers are held substantially out of contact with the walls of the nostrils, but should they bind against the

nostrils, the flexibility of the spring connectors admits of the automatic adjustment of the containers to the various conditions of the nostrils. The inherent spring action of the ring 10, binding about the cartilage septum, holds the device in the nose. The device is light in weight, and thus but a slight pressure of the projections 11 is required. The device may be easily withdrawn from the nose by simply pulling down upon the bridge piece 10, the rounded contacting edges or surfaces of the projections 11 preventing any injury to the cartilage septum in either placing or removing the device.

What is claimed is:—

1. A nasal inhaler comprising a single length of wire wound spirally downward with its coils consecutively increasing in diameter to provide an upwardly tapering container and having its lowermost coil of a reduced diameter to provide a retaining ledge in the bottom of the container, said length of wire being bent abruptly upward against the outer face and at the inner side of said container, the wire being then returned in flaring relation to provide a substantially inverted V-shaped connector at the inner side of the container, said wire being bent to provide a ring shaped bridge piece at the lower end of said connector, and bent outwardly and upwardly from the end of the bridge piece and returned thereon to provide a second opposed connector of substantially inverted V-shape, said wire being then spirally wound upward, the coils being consecutively reduced in diameter to provide a second opposed upwardly tapering container, the wire having its opposite ends at the tops of the opposite containers, the lowermost coil of said second container be-
- ing of reduced diameter to provide a ledge in the bottom thereof, and fillers of absorbent material fitting in said containers and resting on said ledges. 45
2. A nasal inhaler comprising a single length of wire looped at its middle portion to provide a resilient ring for engagement over the lower edge of the cartilage septum and for contact at its ends against the opposite sides thereof whereby to yieldingly hold the wire in place, each strand of the wire being bent outwardly from the ends of the ring and extending a short distance to provide diverging supporting arms, the strands 50 being returned outwardly of the arms and flaring away therefrom to provide braces and constituting with the supporting arms substantially V-shaped spring connectors, the opposite ends of the wire being wound spirally upward outwardly of the connectors into coils consecutively decreasing in diameter to provide a pair of spaced apart upwardly tapering containers, said containers being adapted to fit in the nostrils and 55 said braces extending longitudinally against the inner opposite sides of the containers to hold the same away from the cartilage septum, the lowermost coil of each container emerging from the adjacent spring connector and being of reduced diameter relatively to the lower base end of the adjacent container whereby to provide a ledge in the lower end of each container adapted to support absorbent material therein. 60
3. In testimony, that I claim the foregoing as my own, I have hereto affixed my signature in the presence of two witnesses. 65
